CLAIM

The ornamental design for a faucet and soap dispenser set as shown and described.

DESCRIPTION

FIG. 1 is a front, right, perspective view of the claimed design;

FIG. 2 is a front side view of the claimed design of FIG. 1; FIG. 3 is a rear side view of the claimed design of FIG. 1; FIG. 4 is a right side view of the claimed design of FIG. 1; FIG. 5 is a left side view of the claimed design of FIG. 1; and,

FIG. 6 is a top view of the claimed design of FIG. 1. The ornamental design which is claimed is shown in solid lines in the drawings. The broken lines in the drawings depict portions of the faucet and soap dispenser set and the environmental structure that form no part of the claimed design. Bottom views of each embodiment have been omitted due the disclaimed sink (e.g., basin, receptacle, etc.) blocking or substantially blocking the view of the ornamental features of the claimed design.
